UNITED STATES PATENT OFFICE.

WILLIAM B. ANDERSON, OF CHICAGO, ILLINOIS, ASSIGNOR TO HAGGARD AND MARCUSSON COMPANY, OF CHICAGO, ILLINOIS, A CORPORATION OF ILLINOIS.

MOUNTING FOR BED-BOTTOMS.

1,170,865.

Specification of Letters Patent.

Patented Feb. 8, 1916.

Application filed December 22, 1914. Serial No. 878,519.

To all whom it may concern:

Be it known that I, WILLIAM B. ANDERSON, a citizen of the United States, residing at Chicago, in the county of Cook and State of Illinois, have invented certain new and useful Improvements in Mountings for Bed-Bottoms, of which the following is a specification.

My invention relates to means for yieldingly mounting and maintaining bed bottom structures in bed frames.

One of the objects of my invention is to provide an improved, simplified attachment for a bed bottom structure whereby to yieldingly and pendently support it within a bed frame.

A more specific object of my invention is to provide means whereby a bed bottom structure may be suspended from a bed frame upon closed helical extension springs.

Another object of my invention is to cheapen structures of this class, in one respect by using closed helical extension springs of the same size and character as those used to connect the fabric to the end rails of the ordinary spring bed bottom.

Another object of my invention is to provide a noiseless suspension device, or attachment, in the use of which the amplitude of movement of the suspended bed bottom is greater and the increments of movement are more gradual and less abrupt than when compressible springs are used, upon which the bed bottom is supported, instead of being suspended from the bed frame, as in the use of my invention.

Other and further objects of my invention will become readily apparent, to persons skilled in the art, from a consideration of the following description when taken in conjunction with the drawings wherein:—

Figure 1 is a fragmentary showing of a bed bottom with my suspension attachment associated therewith, part of which is shown 45 in section taken on line 1—1 of Fig. 2. Fig. 2 is a similar view showing a transverse section, taken on line 2—2 of Fig. 1; and showing the manner of securing the attachment to a bed frame.

50 In both views the same reference characters are employed to indicate similar parts.

In the single embodiment which I have chosen to illustrate my invention 5 is a fragment of a side rail of a bed bottom and 6 is

a bracket for supporting the end rails 7 to 55 which the fabric is attached by means of helical springs 9, as usual in such structures.

My attachment is secured, preferably at the four corners of the bed bottom structure to the side rails 5—5 of a bed and consists 60 essentially of the bracket structure 10 provided with a projection 11 adapted to rest upon the bed frame 12 and preferably secured in place by means of the clips 13 underlying the brackets 11 and held by the 65 screws 14. Rising vertically from the lateral projection 11 is a spring support 15 carrying side arms 16 and 17 provided with notches 18 for the reception of the closed helical extension springs 19. The other end 70 of the helical springs may be attached directly to the side rail or tube 5 but for convenience of manufacture I may provide a sleeve 20, having projecting eyes 21 to which the respective springs 19 are connected at 75 their lower ends. Secured substantially centrally of the bracket member 10 is a vertically disposed guide rod 22, as by pin 23 passing through the socket 24 in which the rod 22 is inclosed. The sleeve 20, when the 80 sleeve is used on the side rail 5, is held in place by the set screw 26. The rail 5 and the sleeve 20 are vertically perforated so as to allow considerable lateral movement of the vertically sliding rod 22 therein. The 85 perforations through the sleeve and the side rails are relatively large, but the perforation made through the wooden plug 27, is smaller than the perforations in the rail and sleeve and therefore the guide rod 22, in its 90 vertical movement, makes contact only with the wood bushing 27 and preferably does not touch the sleeve or the side rail and therefore its movement in the wooden bushed hole is substantially noiseless, and inasmuch as 95 there is no relative contact movement of the springs 19, with their supports, they are substantially noiseless. To hold the bracket member 10 in proper relation with the bed bottom I provide a lug 29, which may be an 100 integral part of the member 10, to which is connected a rod or bar, preferably an angle bar 30, as by means of screws 31 and nuts 32. The angle bar 30 extends across the bed bottom and is connected in a similar manner 105 to the part 29 of the device 10 on the corresponding end of the opposite rail. The devices, of which there are four are thus con-

nected in pairs, one pair being located at the head and the other pair at the foot of the bed bottom.

It will be observed, from the foregoing description, that the bed bottom, of which the side rails 5 are parts, is suspended from the side rails 12 of the bed frame, upon the springs 19—19. Any weight upon the bed bottom will cause it to move downwardly, or vertically with respect to the bracket member 10 upon the rod 20, such movement being resisted by the yieldable suspension, closed helical springs and when the unusual weight is removed from the bed bottom the springs 19—19, which are suspended from the side arms 16 and 17, will return the bed bottom to its normal position as shown in Figs. 1 and 2.

The bed bottom is free to move in vertical planes upon the supporting bracket structure 10, but is prevented from moving laterally in any direction by the guide rods 22 that are guided in the sleeves 20 and the side frames 5.

Other means than the projecting eyes 21 from the sleeve 20 may be employed for securing the lower ends of the springs 19 to the rail 5 and other guiding means than the rod 22 may be employed for guiding the structure in its vertical movement, as I do not consider my invention to be limited to the precise construction shown and described but capable of variation in form and disposition of parts within the scope of the appended claims.

Having described my invention, what I claim is:—

1. A device of the character described, for use with a bed frame and a bed bottom comprising a relatively, stationary bracket member, having a laterally extending member for support on a bed frame and a vertically extending cruciform member; a pair of helical springs, each spring having one of its ends connected to one of the arms of the vertical member and the other end to the bed bottom and a guide member secured to said

bracket member to prevent lateral displacement of said bed bottom.

2. In combination with a bed frame and a bed bottom comprising side rails, of a device for yieldingly suspending the bed bottom from said frame comprising a laterally extending member for support on said bed frame, a vertically extending cruciform member, and a guiding member, the latter adapted to pass through a perforation in a side rail of the bed bottom and a pair of helical springs, each connected to an arm of the vertical member and to the said side rail.

3. In combination with a bed frame and a bed bottom comprising side rails, of a device for yieldingly suspending the bed bottom from said frame comprising, a laterally extending member for support on said bed frame, a vertically extending cruciform member and a guiding member, the latter adapted to pass through a perforation in the side rail of the bed bottom, a relatively soft bushing for said guide member to prevent noise when the guide member is moved and a pair of helical springs, each connected to an arm of the vertical member and to said side rail.

4. A device of the character described, comprising a sleeve adapted for connection to a side rail of a bed bottom and perforated for a guide rod, a wood bushing within said sleeve within which said rod is guided; a bracket member connected to the upper end of said guide rod having a laterally extending member for support on a bed frame; a vertically extending member having two side arms and two helical springs, one of each connected to one said side arm and to said sleeve for suspending a bed bottom within a bed frame.

In testimony whereof I hereunto set my hand in the presence of two subscribing witnesses.

WILLIAM B. ANDERSON.
